UNITED STATES PATENT OFFICE

JOHN B. KEMP, OF RIDGEWOOD, NEW JERSEY, ASSIGNOR TO CLARK LOOSE LEAF MANUFACTURING COMPANY, A CORPORATION OF NEW YORK

PAD HOLDER

Application filed August 9, 1930. Serial No. 474,122.

This invention relates to pad holders, and is particularly concerned with the provision of a pad holder for use with continuous dated or calendar pads.

5 It is among the objects of the present invention to provide a pad holder arranged to receive and to support a bodily removable collocated stack of memorandum sheets.

Another object is to provide a pad holder 13 which will removably receive the pad to permit its removal whereby the sheets may be turned to expose the next adjacent sheet without removal of the previous sheet from the stack.

15 Another object is to provide a pad holder adapted to receive and support against accidental displacement the stack of memorandum or calendar sheets which are secured in collocated position by the provision of 20 ring securing members.

Another object of the invention is to provide a pad and pad holder assembly arranged to display any desired sheet of the pad without removal of any other sheet in the pad.

25 Another object is to provide a pad holder which is arranged to receive a pad and to permit its bodily removal, while at the same time preventing accidental longitudinal or transverse dislodgment of the pad from 30 the holder.

Another object is to provide a device of the character set forth, and which is artistic in appearance, simple in construction and may be readily or easily operated.

35 Other objects of the invention will be apparent from a consideration of the following specification taken in conjunction with the accompanying drawing, in which

Fig. 1 is a side elevation of one preferred 40 embodiment of the present invention.

Fig. 2 is a longitudinal section taken on line 2-2 of Fig. 3.

Fig. 3 is a bottom plan view of the pad supporting base, and

45 Fig. 4 is a sectional view taken on lines 4-4 of Fig. 1.

By reference to the accompanying drawing, it will be seen that the invention includes a base plate 10, the front edge of which is 50 upwardly curved, as at 11, the plate being

arranged to be supported in sloping relation to a sloping surface by a pair of suitable supporting legs 12 which, as illustrated in Fig. 4, preferably comprise a tubular pad receiving in its lower end a cushion pad 13 and receiving in its upper end a headed securing screw 14, the head of which bears against the upper face of the plate to removably secure the legs in position.

The base 10 at its forward edge is bifurcated by the provision of a central slot 15, which provides a finger hole through the end by which the ends of the leaves of a pad 16 supported on the surface 10 may be manipulated. The device is specifically designed as 65 a dated memorandum pad or calendar, the leaves being loosely secured in collocated position by suitable securing rings 17. Adjacent the rear edge, the base 10 is provided with elongated apertures 18 which are adapted 70 to receive therethrough the lower portions of the rings so as to prevent transverse movement of the pad upon the base.

The rear end of the base also includes a 75 positioning bracket 19 which is substantially U-shaped, the legs 20 thereof forming the sides of the holder and including end extensions 21 which are adapted to be received through suitable apertures in the base for locking the bracket in position. The intermediate portion of the U constitutes the back 80 of the holder and includes an extended portion 22, which is received through the base to assist in securing a bracket thereon.

The assembly is completed by the provision 85 of the top or cover plate 23, which is secured to inturned flanges 24 of the sides 20 by suitable rivets 25 or their equivalent. It will be understood that the bracket 19 and its cover piece 23 may be of any desired artistic design 90 and may be configured in any appropriate motif.

In the operation of the device it will be seen that the pad may be inserted with the rings attached by permitting the lower portions of the rings to extend through the apertures 18, which will permit the pad to lie directly on the surface 10 and to be moved backwardly till the back of the rings strike the intermediate portion of the U bracket. 100

It will be seen that the circular rings hold the sheets of the pad in offset relation so as to provide a convex outer end thereof. The outer convex end is in part received in and conforms to the end 11 of the base which snugly embraces the pad to prevent accidental longitudinal movement thereof. The sides of the pad are received between the sides 20 of the bracket and the rings are received 10 in downward extension through the apertures 18, thus to prevent transverse displacement of the pad upon the base.

It will be seen by reference to Figs. 1 and 2 that the cover 23 is spaced from the base 15 the width of the pad and therefore snugly embraces the upper edge of the pad and retains the rings in extended position downwardly through the apertures 18. Thus upon removal of the pad the lower edge must be lifted from the curved extension 11 and the 20 pad moved down longitudinally of the base till the rings are free from the cover 23.

It will be seen that the structure provides for the bodily removal of the complete pad. 25 Thus after the pad is removed, the upper sheet may be moved around the rings to lie upon the bottom of the pad and thus the next sheet will be exposed without removal of any of the sheets. By this construction, continuous calendar or memorandum pad is provided in which all memoranda may be permanently retained.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or 45 shown in the accompanying drawings shall be interpreted as illustrative and not in a limiting sense.

Having thus described my invention, what 50 I claim as new and desire to secure by Letters Patent, is:

1. A pad holder including a base, apertured to receive projecting portions of rings, forming binders for a pad of leaves, whereby 55 to prevent sidewise displacement of the pad, said base including a bracket at one end adapted to engage said rings to prevent rearward movement of the pad, said bracket including a cover member adapted to receive 60 the upper portions of the rings to retain

the rings in the apertures of the base against upward movement therefrom.

2. A pad holder including a base, apertured to receive projecting portions of rings, forming binders for a pad of leaves, whereby 70 to prevent sidewise displacement of the pad, said base including a bracket at one end, adapted to engage said rings to prevent rearward movement of the pad, said bracket including a cover member adapted to receive 75 the upper portions of the rings to retain the rings in the aperture of the base against upward movement, said cover member terminating short of the ends of the apertures to permit longitudinal movement of the rings to a 80 position beyond the end of said cover member.

3. A pad holder including a supporting base, apertured to receive portions of rings, forming binders for a pad of leaves, and a 85 bracket carried by the base and forming an end embracing structure for the pad and an abutment for the rings.

4. A pad holder including a supporting base, apertured to receive portions of rings, 90 forming binders for a pad of leaves, a bracket carried by one end of the base and forming an end embracing portion for the pad and an abutment for the rings, and a cover member at said bracket end of said base arranged 95 to contact the upper portions of the rings to retain the rings in the apertures of the base and against upward movement therefrom.

5. A pad holder including a base plate having a plurality of parallel slots adjacent one 100 end thereof to receive projecting portions of rings forming binders for a pad of leaves, and an abutment at the opposite end of said base plate to engage said leaves.

6. A pad holder including a base plate having a plurality of parallel slots adjacent one 105 end thereof to receive projecting portions of rings forming binders for a pad of leaves, a bracket carried by said base plate and adjacent said slots, said bracket carrying a cover 110 plate, said base plate, bracket and cover plate forming a casing adapted to house the rings forming the binders of the pad.

7. A pad holder including a base plate having a plurality of parallel slots adjacent 115 one end thereof to receive projecting portions of rings forming binders for a pad of leaves, a bracket member adjacent said slots, and an abutment member for the leaves of the pad at the opposite end of said base plate, said bracket and said abutment member forming alining means for the leaves.

This specification signed this 4th day of August, 1930.

JOHN B. KEMP. 125
